The ornamental design for a combined sprayer and refill container, as shown and described.

DESCRIPTION

FIG. 1 is a front elevational view of a combined sprayer and refill container showing my new design, the rear elevational view being a mirror image thereof;

FIG. 2 is a top plan view thereof;

FIG. 3 is a bottom plan view thereof;

FIG. 4 is a right side elevational view thereof; and

FIG. 5 is a left side elevational view thereof.

FIG. 1

FIG. 2

FIG. 3

FIG. 4

FIG. 5
